UNITED STATES PATENT OFFICE.

ROBERT E. FRAME AND WILLIAM H. DE GRAFF, OF MICHIGAN CITY, INDIANA,
ASSIGNORS TO HASKELL & BAKER CAR COMPANY, OF MICHIGAN CITY, INDIANA,
A CORPORATION OF INDIANA.

DUMP-CAR

1,111,532.

Specification of Letters Patent.

Patented Sept. 22, 1914.

Application filed June 4, 1913. Serial No. 771,679.

To all whom it may concern:

Be it known that we, ROBERT E. FRAME and WILLIAM H. DE GRAFF, citizens of the United States, and residents of Michigan City, county of Laporte, and State of Indiana, have invented certain new and useful Improvements in Dump-Cars, of which the following is a specification and which are illustrated in the accompanying drawings, forming a part thereof.

The invention relates to cars of the hopper type for carrying coal, ore, and similar freight, and adapted to discharge the load through the bottom of the car.

15 The object of the invention is to provide improved means for controlling the hopper doors, whereby there is obtained simplicity of construction, ease of operation, and a secure fastening for the door.

20 The invention consists in a structure such as is hereinafter described and as illustrated in the accompanying drawings, in which—

Figure 1 is a detail longitudinal central section through the car; Fig. 2 is a detail 25 transverse vertical section on the line 2—2 of Fig. 1; Fig. 3 is a detail plan view of the bottom of the car, some portions being broken away; Fig. 4 is a view in perspective of one of the locks in which the controlling shaft is journaled; and Fig. 5 is a 30 detail in elevation showing a supplemental locking device.

The center sills of the car are shown at 10, 11. A portion of the bottom of the car 35 is represented at 12. A longitudinal deflecting hood for covering the center sills is represented at 13, and a transverse deflecting hood is indicated at 14.

The invention is herein shown and described as applied to a car in which the discharge doors are disposed transversely of the car, though it may be applied to a car in which the doors are differently disposed. One of the discharge doors is represented at 40 15, and is shown as hinged at 16, 17, to an angle-bar 18, mounted on the longitudinal sills of the car, the lower end of the door fitting against the lower end of the inclined bottom 12 of the car and the side walls, as 45 19, of the discharge hopper. A bar 20, here represented as in Z form, is secured across the bottom of the door 15 and may, as indicated in Figs. 2 and 3, extend across the car 50 so as to tie together the doors at opposite

sides of the center thereof, the companion door being indicated in detail at 21.

The door 15 and, when the doors upon opposite sides of the center of the car are secured together as above indicated, the two doors at the corresponding end of the car 60 are controlled by means of a shaft 22, journaled at its outer end in a casting 23, secured to a bracket 23' depending from the side sill 24, and at its inner end in brackets 25, 26, secured to the inner faces of the center sills 10, 11, through one or both of which the shaft may pass. The outer end of the shaft 22 is squared, as shown at 27, for the application thereto of a suitable crank by means of which it may be turned.

Fixed upon the shaft 22 between the center sills is a crank arm 28, here represented as bifurcated and as having at its outer end a longitudinally disposed slot 29 for receiving a pin 30, fixed in a link 31, which is preferably in the form of a rigid continuous bar, as illustrated, and the opposite end of which is pivotally secured to the bar 20, as shown at 32. For the purpose of adjustably attaching the link bar to the bar 20 an eye-bolt 33 is passed through the latter, and a reinforcing bracket 34 attached thereto, the outer end of the bolt 33 being threaded, as shown at 35, and being provided with a nut 36 by means of which the bolt may be adjusted within the bar and bracket, a lock nut 37 being also applied to insure permanence of adjustment.

The brackets 25, 26, are provided at their rearward ends with instanding, downwardly and backwardly inclined flanges, as most plainly shown at 38 in Fig. 4. The pin 30 is prolonged at both ends for engaging the flanges 38 when the door 15 is closed. The link 31 is preferably bent, as shown at 39, so that when it makes contact with the hub 40 of the arm 28 the pin 30 will be past the center of the shaft 22, thus bringing the line of stress from the point of attachment of the link bar to the door upon the pin 30 below this shaft to prevent it from tending to carry the pin 30 upwardly along the flanges 38. The aperture in the crank arm 28 for receiving the pin 30 being elongated, the crank arm is relieved of the duty of sustaining the door in its closed position, substantially all of the load being carried by the flanges 38. By this arrangement

the shaft 22 may be turned without being called upon to draw the door more closely against the frame with which it co-operates.

For the purpose of insuring the tight closing of the door in first assembling the parts, or for the purpose of taking up any wear, the adjustment of the eye-bolt 33 as already described is provided, this adjusting means rendering it possible to bring the pin 30 into proper engagement with the flanges 38 when the door is tightly closed. If found advisable a supplemental locking means may be provided, as represented in Fig. 5, comprising a ratchet wheel 41, fixed upon the outer end of the shaft 22, with which there co-operates a pawl 42, pivotally attached to the bracket 23, a weighted stop 43 being pivoted to the bracket 23 to engage the pawl to prevent its accidental disengagement from the ratchet.

We claim as our invention—

1. In a dump car, in combination, a hopper, a hinged door for closing the discharge end of the hopper, a crank shaft, a link connecting the door and the crank of the shaft, and a fixed shoulder, engageable by the pivot uniting the link and crank, when the door is closed.

2. In a dump car, in combination, a hopper, a hinged door for closing the discharge end of the hopper, a crank shaft, a link connecting the door and the crank of the shaft, its attachment to the latter being shiftable, and a fixed shoulder, engageable by the pivot uniting the link and crank when the door is closed.

3. In a dump car, in combination, a hopper, a hinged door for closing the discharge opening of the hopper, a crank shaft having a longitudinal slot in its crank-arm, a link attached to the door, a pin fixed in the end of the link and engaging the slot in the crank-arm, the end of the pin projecting laterally from the link, and a plate having a shoulder for engagement by the pin when the door is closed, the crank-arm being so disposed that as the closing movement of the door is completed the pin passes beyond the line of attachment of the link to the door and the center of the crank shaft.

4. In a dump car, in combination, a pair of center sills spaced apart, a pair of hop-

5. In a dump car, in combination, a pair of center sills spaced apart, a pair of hoppers located on opposite sides of the center sills, a door for closing the discharge opening of each hopper, such doors being rigidly united, a crank shaft disposed transversely with reference to the car and having its crank arm located between the center sills and being longitudinally slotted, a pair of plates attached one to the inner face of each of the sills, each plate having a shoulder facing backwardly with reference to the doors and being downwardly inclined, and a link connecting the crank arm with the doors, such connection being by means of a pin fixed in the link and engaging the slot in the crank arm and the shoulders of the plates, the crank arm being so disposed that in the final closing movement of the doors the pin is carried beyond a line passing through the crank arm and the point of attachment of the link to the doors. 90

6. In a dump car, in combination, a hopper, a hinged door for closing the discharge end of the hopper, a crank shaft, a link connecting the door and the crank shaft, the pivot uniting the crank and link projecting laterally beyond the parts united, and a pair of fixed shoulders engageable by the ends of such pivot when the door is closed. 95
